BENJAMIN RICHARD DEACON, OF MONTREAL, CANADA.

Letters Patent No. 101,833, dated April 12, 1870.

IMPROVED COAL-BOX

The Schedule referred to in these Letters Patent and making part of the same

To all whom it may concern:

Be it known that I, BENJAMIN RICHARD DEACON, of the city of Montreal, in the district of Montreal, in the Province of Quebec, Dominion of Canada, painter, have invented new and useful Improvements in the Construction of Coal-Boxes, &c.; and I do hereby declare that the following is a full, clear, and exact description of the construction and operation of the same, reference being had to the annexed drawings, where—

Figure 1 represents a part section of the safe.

Figure 2 represents an end elevation of the safe.

This invention has for its object the construction of a coal-box or safe, in a neat form, which embraces the advantages of keeping a large quantity of coal on hand in any required place, and, at the same time, obviates the difficulty found in reaching down into a deep box to extract the coal therefrom, and the loss of having a large portion of the small or powdered coal left remaining or accumulated at the bottom as rubbish, when, had it been used in due proportion with the large, it would be beneficial as fuel, the box being capable of being made to conform in external appearance to any article of furniture, having cubical capacity commensurate with the amount of coal required to be kept on hand at one time, such, for example, as drawers, a sideboard, a book-case, or the like.

In the drawings—

Similar letters of reference indicate corresponding parts.

Letter *a* is the outside shell of the coal-safe.

b, the ordinary bottom, above which is arranged the double inclined inner bottom *c c'*, placed at suitable angles.

d is a regulating board, placed on the front inner side of the shell *a*, by means of which the flow of coal to the mouth *e* may be regulated.

The board *d* may be either fixed in its position or made adjustable at will before the safe is filled.

The door or opening by which the coal is taken out is shown at *f*.

The top or cover *g* may be arranged with a drawer, for ordinary purposes, above or below it.

In the space existing between the inclined bottom *c* and outer bottom *b* a drawer may also be placed for kindling wood, &c.

The safe being arranged substantially as described, it may be filled to the top, as indicated by the crooked dotted line at the upper part of fig. 2.

The coals are prevented from flowing out of the mouth *e* by the action of the regulating-board *d* and second inclined bottom *c'* any faster than required, as shown in fig. 1.

On opening the door *f*, the coal-shovel *h* may be introduced, and, as the small or powdered coal more readily finds its way to the bottom it is taken out in due proportion with the large.

The bottom of the box may be curved, so as to make more room, and the safe may be used for holding grain and other substances as well as coal.

Having now described the construction and operation of my invention, to which I have given the name of "Deacon's Anthracite Coal-Safe," I beg to state that I disclaim all other forms of coal-boxes or safes now in use.

What I claim as my invention, and wish secured by Letters Patent, is—

The combination of the outer shell *a*, double inclined bottom *c c'*, regulating-board *d*, lower opening or mouth *e*, with door *f*, all working together substantially in the manner and for the purpose described.

BENJAMIN RICHARD DEACON.
